[57] **CLAIM**

The ornamental design for a sighting compass/vertical angle metering device, as shown and described.

DESCRIPTION

FIG. 1 is a top plan view of the sighting compass/vertical angle metering device showing my new design;

FIG. 2 is a bottom plan view thereof;

FIG. 3 is a left side elevational view thereof;

FIG. 4 is a right side elevational view thereof;

FIG. 5 is a front side elevational view thereof; and

FIG. 6 is a back side elevational view.

The broken line showing in FIG. 1 is illustrative of environment only.
